UNITED STATES PATENT OFFICE

HORACE D. WEBB, OF ROCHESTER, NEW YORK, ASSIGNOR TO UNITED SHOE MACHINERY CORPORATION, OF PATERSON, NEW JERSEY, A CORPORATION OF NEW JERSEY

DEVICE FOR HOLDING UPPERS IN LASTED POSITION

Application filed June 4, 1929. Serial No. 368,239.

This invention relates to devices for use in the manufacture of shoes for holding the toe portions of the uppers in lasted position. The invention is herein illustrated by reference to the lasting of shoes of a type in which the uppers are made of felt, although it is to be understood that the invention is not limited in utility to the manufacture of shoes made of that particular material or of 10 shoes of the particular type illustrated.

In the manufacture of felt shoes of a well-known type it is the practice to provide an upper of such extent as to overlap the bottom of the last in place of an insole, and before 15 the upper is mounted on the last to stitch its opposite side edges together. The upper is then dampened and a last is inserted, the upper being thereby stretched and conformed to the contour of the last. At the toe end of 20 the upper, however, it is the usual practice to omit the stitching and thus to leave an opening with the margin of the upper free until after the last has been inserted, and thereafter to shape the toe portion of the 25 upper over the last by a toe-lasting operation. In this operation, which is conveniently performed by the aid of toe-embracing wipers of a lasting machine, the margin of the toe portion of the upper is gathered in upstanding 30 folds bunched together in a substantially central location over the bottom of the toe end of the last. To hold the toe portion of the upper in lasted position until it has dried and set in lasted shape, it has been the 35 practice to drive tacks adjacent to the gathered folds, the tacks being thereafter removed and the surplus margin of the upper at the toe trimmed off preparatory to the stitching of an outsole on the bottom of the 40 shoe.

In view of the nature of the felt material, especially its resilient character, it is difficult by the use of tacks, as above described, to hold the gathered folds at the margin of the 45 toe end of the upper in such manner as to insure that the upper will lie substantially flat over the margin of the last bottom around the toe until it has dried. The use, moreover, of lasting tacks, driven necessarily within a 50 comparatively small portion of the area of

the last bottom, tends rapidly to disintegrate the wood of the last. It is accordingly an object of this invention to provide means for holding the upper more satisfactorily in lasted position than heretofore and without 55 danger of damage to the last. For the purpose in view the invention provides a novel device constructed to serve as a binder around the gathered margin of the upper. The device herein shown comprises a member curved 60 to extend partially around the gathered margin at the end and sides of the toe, and another member pivoted on the curved member for forward swinging movement into position to complete the inclosure of the margin of 65 the upper, the arrangement being such that the pivoted member serves by its movement to press the gathered folds of the upper forwardly toward the curved member so that they are held tightly between the two members; and there is also provided means for 70 retaining the pivoted member in operative position. The device thus serves as a clasp for inclosing and holding the gathered margin of the upper. As further illustrated, the 75 curved member is so formed as to adapt it to be pressed into operative position by the wipers of a toe-lasting machine and to be held thereby while the pivoted member is 80 swung into operative position as above described.

The novel features of the invention will now be more particularly described by reference to the accompanying drawings and thereafter pointed out in the claims. 85

In the drawings,

Fig. 1 is a perspective view illustrating how the novel upper-holding device is applied to a shoe by the aid of toe-lasting wipers;

Fig. 2 shows the device as it appears in upper-holding position on the shoe; and

Fig. 3 is a view of the device detached.

In the manufacture of a felt shoe of the illustrated type the felt upper *a* is cut large 95 enough so that its opposite side portions, secured together by a row of stitches *b*, will extend across the bottom of the last in place of an insole. The opposite side edges of the upper are thus stitched together while the 100

upper is off the last, after which the upper is moistened and the last is inserted to stretch and shape it in the required shoe contour. It is customary to terminate the row of stitches *b* at such a point that an opening is left at the toe portion of the upper, and after the insertion of the last this portion of the upper is shaped to the contour of the toe end of the last by a toe-lasting operation. In this operation it is customary to use the toe-embracing wipers 10 of a toe-lasting machine to wipe the upper inwardly over the margin of the last bottom at the end and the sides of the toe and to gather the surplus margin of the upper in a plurality of more or less upstanding folds *c* bunched together in a substantially central location over the bottom of the toe end of the last. The lasting machine is not shown in detail, but it will be understood that it comprises means whereby the wipers are moved lengthwise of the shoe and are closed to wipe the upper over the last bottom and to gather its margin in a bunch of folds and also means whereby the wipers may be moved heightwise of the shoe to increase their pressure on the upper. During the wiping operation the operator may pull the upper more or less by engaging its margin with hand pincers. After the toe portion of the upper has been worked into lasted position as above described, it is necessary to hold it until it has set. For this purpose the present invention provides a novel device adapted to be applied around the gathered margin of the upper as a binder or clasp. The device herein shown comprises a substantially U-shaped member 12 curved to extend partially around the gathered margin of the upper at the end and sides of the toe, and another member or arm 14 pivoted at 16 on the member 12 for movement into position to extend laterally of the shoe at the rear of the gathered margin to complete the inclosure of said margin. It will be seen that the arm 14 is pivoted on one end of the member 12 for forward swinging movement toward the bunch of folds *c* and toward the end of the toe in a plane substantially parallel to the last bottom, approaching in that movement the other end of the member 12 which it finally overlaps. The arm 14 is thus arranged to engage the rearmost folds *c* and press them forwardly toward the member 12 in order that the folds will be tightly clasped and held, and for more effective results in this respect it is provided with a projection 18 for engagement with the folds. To hold the arm 14 in operative position there is provided a catch 20 comprising a bent-up portion of the member 12 over which the end of the arm rides as it is moved into operative position. The member 12, as herein shown, is formed of resilient sheet metal with one of its lateral surfaces arranged to face the bottom of the last, and

the resiliency of the member facilitates movement of the arm 14 over the catch 20, as above described, and also facilitates release of the arm from the catch in removing the device from the shoe. The arm 14 is likewise formed of sheet metal and has an upturned lug 22 thereon to assist in applying the device to the shoe and in removing it. The device is preferably applied to the shoe by the aid of the wipers 10, and to this end the member 12 has thereon an upstanding lug 24 which provides a shoulder arranged to be engaged by the edges of the wipers to press the member rearwardly against the gathered margin of the upper.

In the use of the device above described, the operator, after wiping the toe portion of the upper inwardly over the last bottom and gathering its margin in a centrally located bunch of folds *c* by aid of the wipers 10, partially retracts and lifts the wipers and places the device on the shoe bottom with the member 12 adjacent to the folds at the end and sides of the toe and projecting partially under the wiping faces of the wipers, the arm 14 being swung to open position, and then by means of the wipers he presses the member 12 rearwardly and also downwardly upon the shoe bottom, as illustrated in Fig. 1. Then, while holding the member 12 pressed against the upper by the wipers, he swings the arm 14 forwardly into position to be held by the catch 20, the projection 18 on the arm engaging the rearmost folds *c* and pressing them forwardly toward the member 12. The shoe is then removed from the lasting machine with the upper-holding device thereon in the position illustrated in Fig. 2. It will be understood that the folds of the upper tend to spread out over the device and thus assist in preventing it from slipping upwardly. The device is left on the shoe until the upper has dried and set in lasted shape, after which it is removed and the surplus margin of the upper is trimmed off.

It will be evident that by use of the device described the gathered margin of the upper is held securely in such manner as to maintain the entire toe portion of the upper tightly in lasted position with that portion of the upper that overlies the margin of the last bottom at the end and sides of the toe in a substantially flat condition, without danger that any of the folds may extend itself outwardly toward the edge of the last bottom by reason of the resiliency of the felt material. It will also be evident that the device may be used repeatedly in lasting different shoes.

Having described the invention, what I claim as new and desire to secure by Letters Patent of the United States is:—

1. A device for holding the surplus margin of the toe portion of an upper gathered in folds in a substantially central location over

the bottom of the toe end of a last, comprising a member formed to extend partially around the gathered margin of the upper, and another member movable relatively to said first member into position to complete the inclosure of said margin.

2. A device for holding the surplus margin of the toe portion of an upper gathered in folds in a substantially central location over the bottom of the toe end of a last, comprising a member curved to extend partially around the gathered margin of the upper at the end and sides of the toe, and another member arranged to extend laterally of the shoe at the rear of the gathered margin to complete the inclosure of said margin.

3. A device for holding the surplus margin of the toe portion of an upper gathered in folds over the bottom of the toe end of a last, comprising a substantially U-shaped member formed to extend partially around the gathered margin of the upper, and another member pivoted on one end of said U-shaped member for movement toward or from the other end thereof.

4. A device for holding the surplus margin of the toe portion of an upper gathered in folds in a substantially central location over the bottom of the toe end of a last, comprising a member formed to extend partially around the gathered margin of the upper at the end and sides of the toe, and another member mounted on said first member for movement forwardly toward the end of the toe at the rear of the gathered margin.

5. A device for holding the surplus margin of the toe portion of an upper gathered in folds in a substantially central location over the bottom of the toe end of a last, comprising a member formed to extend partially around the gathered margin of the upper at the end and sides of the toe, and an arm pivoted on one end of said member for swinging movement forwardly toward the end of the toe at the rear of the gathered margin, said arm being arranged to press the folds of the upper forwardly by its swinging movement.

6. A device for holding the surplus margin of the toe portion of an upper gathered in folds in a substantially central location over the bottom of the toe end of a last, comprising a member curved to extend partially around the gathered margin of the upper at the end and sides of the toe, and another member pivoted on one end of said curved member for swinging movement forwardly toward the end of the toe to a position adjacent to the other end of the curved member, said pivoted member having a projection thereon arranged to engage the folds of the upper and press them forwardly.

7. A device for holding the surplus margin of the toe portion of an upper gathered in a bunch of folds over the bottom of a last, com-

prising a clasp having different members relatively movable into holding relation to the bunch of folds.

8. A device for holding the surplus margin of the toe portion of an upper gathered in a bunch of folds over the bottom of a last, comprising a clasp having parts pivotally connected for relative movement into position to embrace the folds and press them together.

9. A device for holding the surplus margin of the toe portion of an upper gathered in a bunch of folds over the bottom of a last, comprising a clasp having parts pivoted together for relative movement in a plane substantially parallel to the last bottom into holding relation to the bunch of folds, and means for retaining the parts of the clasp in that relation.

10. A device for holding the surplus margin of the toe portion of an upper gathered in a bunch of folds over the bottom of a last, comprising a member formed to extend partially around the bunch of folds, an arm pivoted on one end of said member for movement to a position adjacent to the other end of the member to complete the inclosure of the bunch of folds, and means on said other end of the member for retaining the arm in that position.

11. A device for holding the surplus margin of the toe portion of an upper gathered in a bunch of folds over the bottom of a last, comprising a member formed to extend partially around the bunch of folds at the end and sides of the toe and having a shoulder thereon arranged to be engaged by the wipers of a lasting machine to press the member rearwardly against the bunch of folds, and another member mounted on said first member for movement into position to extend laterally of the shoe at the rear of the folds while the first member is held by the wipers.

12. A device for holding the surplus margin of the toe portion of an upper gathered in a bunch of folds over the bottom of a last, comprising a curved member formed to extend partially around the bunch of folds at the end and sides of the toe and so constructed as to adapt it to be engaged both by the edges and by the wiping faces of the wipers of a lasting machine to press the member against the upper, and an arm pivoted on one end of said member for movement into position to complete the inclosure of the bunch of folds while the member is held by the wipers.

13. A device for holding the surplus margin of the toe portion of an upper gathered in a bunch of folds over the bottom of a last, comprising a member formed of resilient sheet metal and curved to extend partially around the bunch of folds with one of its lateral surfaces facing the bottom of the last, and an arm pivoted on one end of said mem-

ber for movement into overlapping relation to its other end, a portion of said other end of the member being bent into position to serve as a catch for holding said arm in operative position.

5 In testimony whereof I have signed my name to this specification.
